MAGNETRON

Ernest G. Linder, Philadelphia, Pa., assignor to
 Radio Corporation of America, a corporation of
 Delaware

Application September 30, 1938, Serial No. 232,489

9 Claims. (Cl. 250—36)

My invention relates to improvements in magnetrons in which greater efficiency and improved electron control are attained by providing end plate electrodes which are divided into two or more segments and which, in one form of my invention, are coupled to the anode electrodes.

It is an object of my invention to provide means for increasing the electron control in a magnetron.

10 It is another object of my invention to provide sectionalized end plate electrodes in a magnetron, each section of which may be energized independently.

15 It is a further object of my invention to increase the efficiency of a magnetron by properly relating the phase of the alternating current voltage on the anode electrode to the voltage on the end plate or end plate segments.

20 A further object of my invention is to provide a new and improved form of end plate for magnetrons.

A still further object of my invention is to provide means for increasing the efficiency of a magnetron oscillator.

25 It is a still further object of my invention to provide means for reducing the electric field distortion which is caused by end plates in a magnetron.

The invention will be better understood from 30 the following description when considered in connection with the accompanying drawing. Its scope is indicated by the appended claims.

Referring to the drawing:

Figure 1^a is a schematic drawing of a magnetron oscillator having sectionalized end plates with an unequal direct current voltage on the sections, and Figure 1^b is an end view of the end plate illustrated in Figure 1^a;

Figure 2^a is a schematic drawing of a magnetron oscillator having sectionalized end plates which are coupled to the anode electrodes of a split anode magnetron, and Figure 2^b is an end view of the end plates illustrated in Figure 2^a; and

45 Figure 3^a is a schematic drawing of a magnetron oscillator having sectionalized end plates which are coupled to the anode electrodes by a resonant circuit, and Figure 3^b is an end view of the end plates illustrated in Figure 3^a.

50 I have illustrated my invention by means of a magnetron oscillator circuit, but my invention is applicable to amplifier and detector circuits as well.

End plate electrodes have been utilized in magnetron oscillators for the purpose of creating an

electron flow in the direction of the axis of the cathode, and to reduce electron bombardment on the glass container. As usually employed a high direct current potential is applied to the end plates. The normal direct potential near the cathode is low in the absence of end plates. The end plates, however, introduce a high direct current potential in the region of the cathode, which distorts the normal electric field within the tube, and causes the electron paths to be nonuniform. 5 That is, electrons which are emitted near the ends of the cathode are attracted directly to the end plates, and thus do not have a chance to rotate about the cathode. Such electrons do not assist in the operation of the tube and therefore 10 assist in the operation of the tube and therefore 15 reduce its efficiency.

I have found that greater efficiency is obtained if this distortion is eliminated by sectionalizing the end plate in such a manner that high direct current potentials may be applied in the region 20 near the anode electrodes and lower direct current potentials may be applied in the region near the cathode. This is accomplished in the manner illustrated in Figs. 1^a and 1^b, to which reference is now made. Similar reference numerals 25 refer to similar elements throughout the drawing.

A pair of anodes 5, 7, having semi-cylindrical surfaces are concentrically arranged about a cathode 9, within an evacuated envelope 10. The anode electrodes are connected to an antenna 11 by means of a transmission line 13, 15. Direct current potential is supplied to the anode electrodes by a battery 19, or the like, which is connected through a radio frequency choke coil 17 to the mid-point of the antenna, to one end 30 of the cathode, and to ground. The cathode is heated by a battery 21. A magnetic field is supplied by a source, such as a permanent magnet, electromagnet or solenoid, which is not shown. The field is indicated by the arrow labeled "magnetic field," and substantially parallel to the axis 35 of the cathode.

It will be seen that the elements and connections so far recited are those of the usual magnetron oscillator. According to my invention, I 45 have provided at each end of the anode electrodes, and slightly spaced therefrom, a pair of end plates comprising segments 23, 25. Each end plate is perpendicular to the cathode axis, and consists of an outer annular segment 23, and an inner circular segment 25. The outer segments 22, 23 are both connected to a high voltage tap on the battery 19, and the inner segments 25, 26 are likewise connected to the battery 19, but preferably at a lower potential. 50

I have also found that the usual end plate, and in fact the end plate structure illustrated in Fig. 1^a, interferes with the alternating current field in the region of the anode electrodes. This is 5 because the end plates are usually at ground potential with respect to radio frequency, or at least at some indeterminate potential which is the inherent result of the inclusion of a finite length of conductor between the end plate and 10 the battery. I have found that the performance of a magnetron oscillator can be further improved by causing the end plate to assume an alternating potential.

One method of accomplishing this further improvement in accordance with my invention is 15 illustrated in Figs. 2^a and 2^b, to which reference is now made. Fig. 2^a differs from Fig. 1^a only with respect to the end plates which are now not only sectionalized as in Fig. 1^a, but the outer 20 annular segment 27 is also divided along a line through its diameter, thus permitting the upper and lower half to assume the instantaneous high frequency potential of the respective adjacent anode section. Each outer semi-annular segment 25 27 is coupled to the adjacent anode by the capacity between the segment and flanges 29 which extend radially from each end of the anode segments 5 and 9. Direct current potential is applied to the outer end plate segments 27 30 through radio frequency chokes 31. The inner circular end plate segment 33 is connected directly to a suitable tap on battery 19, as before. In order to permit close coupling between the outer end plate segments and the anode sections, 35 the cathode 9 is brought out through a centrally located hole in the inner end plate.

As a result of the foregoing arrangement, each 40 end plate segment follows the potential fluctuations of the anode section to which it is adjacent. This prevents the distortion of the high frequency field. Simultaneously the steady electric field near the end plates, due to the steady 45 anode potential, is not distorted in the cathode region, as the end plate direct current potential is much less near the cathode than in the region near the anode.

I have discovered, further, that still more efficient oscillations are obtained if the phase of 50 the alternating potential on the end plate segments is displaced somewhat with respect to the potential of the respective adjacent anode sections. In accordance with one embodiment of my invention, this is accomplished by coupling each end plate segment to its adjacent anode by a 55 tuned circuit. Referring to Figs. 3^a and 3^b, a pair of semi-circular end plates 35, 37 are utilized at each end of the usual split anode sections 5, 7 of the magnetron. To simplify the illustration, sectionalizing for direct current potential control 60 has not been shown in Figs. 3^a and 3^b, but this feature may be added in the manner shown in Figs. 2^a and 2^b.

The tuned circuits 39 couple respective end 65 plate segments to the nearest end of the adjacent anode section 5 or 7. The tuned circuits have been illustrated as parallel line circuits, but for the lower frequencies it may be more convenient to utilize lumped inductors. Fig. 3^b is a schematic end view of the end plates used in 70 Fig. 3^a, showing more clearly their semi-circular shape.

It has been found also that magnetrons of the usual type utilizing circular end plates are improved when the end plate is coupled to the anode by a tuned circuit in the manner described.

Where magnetrons are used having anodes which are split into four sections, the end plates would, of course, be divided into four equal sections.

I have thus described an improved magnetron oscillator which utilizes sectionalized end plates 5 to reduce the field distortion within the tube. I have also described several ways of connecting such end plates to the anode electrodes in order to obtain maximum efficiency.

I claim:

1. In a device of the character described, a magnetron comprising an anode, a cathode, and sectionalized end plates, respective sections of which are adapted to be operated at different potentials with respect to said cathode, and means 15 for producing a magnetic field.

2. In a device of the character described, a magnetron comprising an anode, a cathode, and sectionalized end plates, means for producing a magnetic field, and means, for applying different 20 potentials between said cathode and the sections of said end plates, for reducing the distortion of the electric field within said magnetron.

3. In a device of the character described, a magnetron comprising an anode, a cathode, and 25 sectionalized end plate electrodes, means for producing a magnetic field, and means for applying different potentials between said cathode and respective sections of said end plates, for reducing the distortion of the high frequency alternating 30 electric field within said magnetron.

4. In a device of the character described, a magnetron comprising a cathode, a split anode and sectionalized end plate electrodes, means for producing a magnetic field, and means for maintaining different sections of said end plate electrodes at different direct current potentials with 35 respect to said cathode.

5. In a device of the character described, a magnetron comprising a cathode, a concentric 40 split anode, and sectionalized end plate electrodes, means for producing a magnetic field, means for maintaining a section of said sectionalized end plate at the alternating current potential of an adjacent anode section, and means for maintaining 45 said section at a different direct current potential with respect to said cathode from that of said adjacent anode and from that of the other section of said sectionalized end plate.

6. In a device of the character described, a 50 magnetron comprising a cathode, a concentric split anode, and sectionalized end plate electrodes, said end plate electrodes comprising an outer annular section and an inner concentric circular section, means for producing a magnetic field 55 whose lines of force are parallel to said cathode, and means for independently applying direct current potentials between cathode and the inner and outer sections of said end plate electrodes.

7. In a device of the character described, a 60 magnetron comprising a cathode, a split anode, and two sectionalized end plate electrodes, each of said sectionalized end plates comprising semi-circular elements arranged in a plane perpendicular to said cathode and adjacent to the ends of 65 said split anode electrodes, means for applying direct current potentials between cathode and said anode and between cathode and said end plate electrodes, and means for coupling said end plate sections to adjacent anode sections.

8. In a device of the character described, a 70 magnetron oscillator comprising a cathode, a split anode and two sectionalized end plate electrodes, each of said end plate electrodes comprising two equal semi-annular sections enclosing an inner 75

5 circular section which is in the same plane, said sectionalized end plate electrodes being perpendicular to said cathode, and one being adjacent each end of said anode electrode, means coupling said semi-annular sections to respective anode sections, means for applying a direct current potential between said cathode and said semi-annular sections, means for applying different direct current potentials between said cathode and said 10 circular end plate sections and said anode sections, and means for producing a magnetic field.

10 9. A magnetron comprising cathode, anode and

end plate electrodes, means for producing a magnetic field parallel to and surrounding said cathode, an oscillatory circuit connected to said anode for producing an oscillatory voltage on said anode and coupling means connected between said anode and end plate electrodes for applying said oscillatory voltage to said end plate electrodes, said coupling means providing a predetermined phasal relationship between the voltage on said anode electrode and that applied to 10 said end plate electrodes.
